Primary Examiner — Richard E Chilcot

(74) Attorney, Agent, or Firm — Thomas | Horstemeyer, LLP

(57) **CLAIM**

The ornamental design for coffee machine, as shown and described.

DESCRIPTION

2. Coffee machine

2.1 : Front

2.2 : Back

2.3 : Top

2.4 : Bottom

2.5 : Right

2.6 : Left

2.7 : Perspective

2.8 : Perspective

The broken lines are included to show features that form no part of the claimed design. The parallel thin lines and the radial thin lines in the representation represent contours only and do not illustrate an ornamentation or decoration on the surface of the product.

1 Claim, 8 Drawing Sheets(56)
